GEORGE SMITH AND GODFREY SMITH, OF NEW YORK, N. Y.

Letters Patent No. 74,858, dated February 25, 1868.

IMPROVEMENT IN BOOTS AND SHOES.

The Schedule referred to in these Letters Patent and making part of the same.

TO ALL WHOM IT MAY CONCERN:

Be it known that we, GEORGE SMITH and GODFREY SMITH, of the city, county, and State of New York, have invented a new and useful Improvement in Ornamenting Boots and Shoes; and we do hereby declare that the following is a full, clear, and exact description thereof, which will enable others skilled in the art to make and use the same, reference being had to the accompanying drawings, forming part of this specification.

This invention relates to a new and improved mode of ornamenting boots and shoes, designed as a substitute for and an improvement upon the ordinary mode of producing ornaments by crimping the leather through the medium of dies.

Crimping by means of dies is attended with some disadvantages. The dies are liable to cut and injure the leather, and the prominences formed by the dies become very much depressed during the process of "lasting" the boot or shoe.

Our invention consists in stitching a piece of leather or other suitable material to the inner side of the upper of the boot or shoe, at the part where the ornament is to be produced, the stitches being done in such a manner as to form pockets or channels to receive cords, which give the desired prominences to form the ornament. In the accompanying sheet of drawings—

Figure 1 represents the outer side of the upper of a boot or shoe, ornamented according to our invention.

Figure 2, a longitudinal section of the same, taken on the line *x x*, fig. 1.

Figure 3, a transverse section of the same, taken in the line *y y*, fig. 1.

Similar letters of reference indicate corresponding parts.

A represents a portion of the upper of a boot or shoe, ornamented, in this instance, by a series of parallel prominences, *a*, like those now formed by pressure between dies. To the under side of the upper, *A*, a piece of thin leather or other suitable material, *B*, is stitched. This stitching may be done very rapidly by means of a sewing-machine, such as is constructed for sewing leather. The stitching is made in such a manner as to form pockets or grooves, through which cords *b* are drawn, shown in figs. 2 and 3, and by means of these cords the prominences *a* are produced. The cords remain permanently in the pockets or grooves, and hence the prominences *a* cannot become depressed or flattened, as is the case with those produced by dies. After the cords are inserted, the ends of the pockets or grooves may be closed by stitching, and the prominences or ornamented surface worked over by a proper-shaped tool, in order to give a finished appearance to the raised surfaces; or the cord may be placed between the leathers before they are stitched together.

By this simple means the raised surfaces will always remain in bold relief, and the ornament can be made much cheaper than by the old or present process of forming or crimping by dies.

This improvement is not confined to any particular form or design, but is applicable to all that may be produced by the crimping process.

Having thus described our invention, we claim as new, and desire to secure by Letters Patent—

The ornamenting of boots and shoes by stitching a piece of leather or other suitable material to the inner side of the upper in such a manner as to form pockets or grooves between the upper and the inner material, to enclose cords of any suitable material, by which prominences are given the outer or external surface of the upper, substantially as shown and described.

GEORGE SMITH,
GODFREY SMITH.
